EDWIN HATHAWAY PERRY, OF BOSTON, MASSACHUSETTS.

Design No. 4,799, dated April 11, 1871.

DESIGN FOR WATCH-PLATE.

The Schedule referred to in these Letters Patent and making part of the same.

To all to whom these presents shall come:

Be it known that I, EDWIN HATHAWAY PERRY, of Boston, in the county of Suffolk and Commonwealth of Massachusetts, have made an invention of a new and desirable Design for the Top Plate of a Watch Movement; and do hereby declare the following description to embrace the nature of such invention, due reference being had to the drawing or diagram accompanying such description, and which illustrates clearly the character of the design.

In this plate the pivots of the main, center, (or second,) third, fourth, and fifth wheels of the train of the watch movement find their bearings; therefore the plate constitutes a bridge for such wheels, and, while supporting them, exposes them partially to view, and, with its graceful curves, produces an elegant and pleasing design.

This plate is a sectoral one, and embraces in superficial area somewhat more than a half circle, its inner boundary or combined radii being, substantially, on a right line projected through the pivots of the center and fourth wheels, while its intercepted arc is determined by this line, and is, therefore, a continuous or unbroken semicircle, the swells of the radii constituting the excess of the superficial half circle of the plate.

The accompanying sketch or diagram represents, at A, a sectoral flat plate, the intercepted arc of the sector, which constitutes the outer and major boundary of the plate, being shown at b, while the pivot-bearing of the main wheel is shown at c, that of the center or second wheel at d, of the third wheel at e, of the fourth wheel at f, and of the fifth wheel at g.

One radius of the sector, projected from the pivot *d* as a center toward the fifth-wheel pivot, is composed of a small portion of the semicircular bearing of the said pivot *d* and a greater part of the surrounding bearing of the fifth-wheel pivot *g*, the line intervening between these points being curved inward and composed of two segments of a circle, one of which is struck from the pivot of the balance as a center, and the other from the point *i* of the diagram; the remaining portion of this radius being a line curved inward, and extending from the bearing of said fifth-wheel pivot to and intercepting the arc *b* on the right line *j*, which, as before stated, is projected through the pivots of the center and fourth wheels of the train.

The opposite radius is composed of a sinuous line, resembling "Hogarth's line of beauty," the greater part of which is a swelling curve, projecting beyond the line *j*, and intercepting, with an obverse short curve, the arc *b* on such line, thus completing the entire contour of the plate, and producing the design constituting the subject-matter of my present invention.

This plate may be used with either side uppermost.

I claim—

The design herein explained, and as particularly shown in the accompanying diagram.

EDWIN HATHAWAY PERRY.
